UNITED STATES PATENT OFFICE.

GEORGE ASHWORTH AND ELIJAH ASHWORTH, OF MANCHESTER, COUNTY OF LANCASTER, ENGLAND.

BEND FOR CARDING-ENGINES.

SPECIFICATION forming part of Letters Patent No. 359,529, dated March 15, 1887.

Application filed October 29, 1883. Serial No. 110,305. (No model.) Patented in England May 15, 1883, No. 2,432.

To all whom it may concern:

Be it known that we, GEORGE ASHWORTH and ELIJAH ASHWORTH, residing at Manchester, county of Lancaster, England, and subjects of the Queen of Great Britain and Ireland, have invented certain Improvements in the Bends of Carding-Engines, (for which we have obtained a patent in Great Britain, No. 2,432, dated May 15, 1883,) of which the following is a specification.

Our invention relates to the curved bends upon which the ends of the flats travel in their movement partly around the cylinder of the carding-engine. As ordinarily constructed these bends are made to be slightly flexible and are adjusted, approximately, by drawing in or pushing out the ends by means of screws, so as to obtain a curve of the required radius. This method does not furnish means for obtaining a surface which shall be truly concentric with the axis of the main cylinder. To obtain a truly concentric bend or rail we cast a curved rail in one piece with the pedestal, in which is formed or fitted the bearing for the shaft of the main carding-cylinder, and we true the periphery of the rail to a segment of a true circle having the axis of the cylinder-bearing for its center.

The accompanying drawing represents a side view of the curved rail and pedestal and a portion of the engine-framing on which they are mounted.

In the drawing a curved rail, *a*, is connected by cross-pieces *b b* with the pedestal *c*, in which are fitted the bearings *d* for the shaft of the main cylinder. The parts *a b c* are cast together in one piece. The frame so formed is turned in a lathe, so as to obtain an outer surface at *e e* which shall be truly concentric with the axis of the bearing *d*. To effect this a mandrel may be fixed in the bearing, and the frame may be turned on the mandrel-centers, or the frame may be otherwise adjusted in the lathe. The frame is bolted to the top of the bottom engine-framing, *f*, and takes the place of the ordinary upper side frame. A similar frame or rail is secured on each side of the engine-framing.

When the main carding-cylinder is placed in its working position, with its shaft mounted to revolve in the bearings *d* on each side of the engine, the periphery *e* of the rail *a* will

be truly concentric with the axis of the cylinder, in consequence of the said periphery having been turned from the centers of the said bearings. The bearings *d* are supported with the pedestal upon the upper end of a screwed pillar, *g*, which passes through a tapped hole in the bottom of the pedestal and is furnished with a lock-nut. Whenever necessary, the main cylinder can be raised and lowered by turning the said screwed pillar in order to make the axis of the cylinder to be concentric with the periphery at *e*. The ends of the flats travel upon the turned peripheries of the rails or frames *a* on each side of the engine, or upon metal ribbons, which we apply upon such peripheries in accordance with another invention for which we have made application for a patent, (said application filed October 29, 1883, Serial No. 110,306.) In some cases we may turn the rail *a* to a complete circle extending below the framing *f*.

Our invention is applicable to various constructions of carding-machines in which traveling flats are used, an example being that shown in our British Patent No. 2,916 of 1879.

We claim as our invention—

1. The combination of the lower frame of a carding-engine with a curved rail, *a*, having a bearing-pedestal, *c*, in one piece with the rail, the periphery of the latter being concentric with the bearing for the axis of the main cylinder, substantially as set forth.

2. The combination of the lower frame of a carding-engine with an upper side frame and a bearing-pedestal cast in one piece with the said upper side frame, the periphery of the latter being concentric with the bearing for the axis of the main cylinder, substantially as described.

3. The combination of the lower frame of a carding-engine with an upper side frame, a pedestal, *c*, cast in one piece with the latter, and a bearing and an adjusting-screw, *g*, substantially as specified.

In testimony whereof we have signed our names to this specification in the presence of two subscribing witnesses.

GEO. ASHWORTH.

ELIJAH ASHWORTH.
